UNITED STATES PATENT OFFICE.

HOWARD J. MURPHY, OF READING, MASSACHUSETTS, ASSIGNOR TO ALEMITE MANUFACTURING CORPORATION, OF CHICAGO, ILLINOIS, A CORPORATION OF DELAWARE.

LUBRICATING APPARATUS.

Application filed October 9, 1928. Serial No. 140,515.

This invention aims to provide improvements in lubricating apparatus and more particularly to improvements in so-called "lubricant guns".

5 In the drawings, which illustrate a preferred embodiment of my invention:

Figure 1 is a side elevation of a lubricant gun.

Fig. 2 is a longitudinal section through 10 the front head and nozzle of the gun, shown engaged over the end of a nipple before coupling and valve opening;

Fig. 3 is a section similar to Fig. 2, but showing the relation of parts after coupling 15 and valve opening;

Fig. 4 is a plan view of the front head and nozzle connected with the nipple, the outer sleeve being removed to show a pin and slot;

20 Fig. 5 is an end elevation of the front head, nozzle and nipple;

Fig. 6 is a rear view of the same; and

Figs. 7, 8, 9 and 10 are sections on the lines 7—7, 8—8, 9—9 and 10—10, respectively, of Fig. 2.

Referring to the embodiment of my invention illustrated in the drawings, I have shown a lubricant gun for making a connection with a lubricant-receiving nipple and 30 for forcing lubricant under pressure to a part to be lubricated (not shown).

The gun includes a barrel 1, a front head 2 providing an integral nozzle portion 3, a removable rear head 4 to permit filling of 35 the barrel 1, and a piston 5 (shown in dotted lines in Fig. 1) in the barrel for compressing the lubricant. The piston is secured to the end of a stem 6 threaded through the rear head 4, and a handle 7 is secured to the outer 40 end of the stem for turning it.

In the preferred embodiment of my invention, as illustrated by the drawings, the nipple includes a body threaded at one end 45 8 for engagement with a part to be lubricated. At the central portion of the body, I provide three projections 9 which provide a generally triangular cross-section at this point and, at the end opposite the screw-threaded end, I provide a generally circular 50 smoothed head portion 10, as shown in Figs. 2 and 3.

The nozzle portion 3 is in the form of a 55 hollow sleeve having an opening 11 in its outer end shaped like a triangle to fit over the projecting portions 9 of the nipple. Im-

mediately behind the aperture 11, the nozzle presents coupling shoulders 12, adapted to underlie the projections on the nipple. Inferiorly of the nozzle sleeve, I provide a coupling part 13 presenting a triangular shaped 60 aperture passing entirely therethrough to receive the projecting portions 9 of the nipple, and to prevent turning between this coupling part and the nipple. The coupling part fits into the nozzle so that the nozzle may be 65 turned relative thereto, but is held against longitudinal movement by a spring ring 14 snapped into a groove 15 formed in the inner wall of the nozzle sleeve 3.

A sealing part 16, triangular in cross-section, is fitted into the coupling part 13 and anchored against longitudinal movement by a pin 17, which passes through one side of the coupling part 13 and sealing part 16 as shown in Figs. 2, 3 and 8. The sealing 70 part 16 is bored and carries at its outer end a flexible washer 18 for making a fluid-tight joint with the end of the lubricant-receiving nipple. A recess is provided behind this washer 18 so that the lubricant may press the 80 washer tightly against the nipple.

A reciprocable valve part 19 is also located within the nozzle part 3, and has a portion which fits the inner wall of the nozzle sleeve, and another portion which is triangular in 85 cross-section and fits within the coupling part 13, to prevent relative rotation between these two parts. Relative reciprocation and rotation between this valve part 19 and the nozzle 3 is governed by coordinated pin and 90 slot connections as indicated by Figs. 2, 3, 4 and 9. Opposed pins 20, 20 are secured to the valve part 19 and present smooth portions which enter opposed slots 21, 21 cut through the nozzle sleeve. These slots are preferably 95 concealed by a separate sleeve 22, which fits over a portion of the nozzle sleeve and is threadedly connected to the head 2 of the gun.

The valve 23 may be formed as a part of the valve part 19, but I prefer, as illustrated, 100 to have the valve slidably in the valve part with a portion of the valve stem 24 sliding in the bore of the sealing part, as shown in Figs. 2 and 3. A sealing washer 25 is connected to the end of the stem 24 to prevent 105 leakage of lubricant around the stem.

The valve seat part 26 is assembled with a part 27, screwed into the head 2, as shown in Figs. 2 and 3, in such a manner that it may reciprocate slightly; it being limited in 110

its movement in one direction by the shoulder 28, and in the opposite direction by the spring ring 29 snapped into the groove 30, in the part 27, to hold the seat part in assembly with the part 27. The seat may be provided directly on the part 27, but I prefer to provide it on a somewhat flexible leather part 31 carried by the seat part.

10 Cup washers 33 and 34 respectively are placed in back of the valve part 19 and valve seat part 26 to prevent leakage of lubricant around these parts, as shown in Figs. 2 and 3.

15 The operation of the above described device may be as follows. Assuming that the nipple is attached to a part to be lubricated, and held rigid by such attachment, the coupling end of the nozzle may be slipped over the nipple until the end of the nipple bears against the sealing washer 18. The triangular portion fits into the coupling part 13 and prevents rotation between it and the nipple, and also the sealing and valve parts 16 20 and 19, as shown in Fig. 1. If now the barrel 1 be turned in a clockwise direction, the nozzle 3 will be turned relative to the parts held against rotation. As the pins 20, 20 are held against rotation, because the valve part 19 cannot turn, the slots 21, 21 will move relative to the pins. The first movement will 25 occur between the straight portions of the slots and the pins and this provides the coupling operation, because the shoulders 12 turn and engage behind the projections 9 on the nipple. Thereafter the inclined portions 30 of the slots will be presented to the pins, and the valve 23 and valve part 19 will be free to move longitudinally. By turning the handle 7, the lubricant in the barrel will be compressed and the lubricant will act upon the 35 valve to press it and the valve part forward to unseat the valve and permit lubricant under pressure to flow through the passage 32 in the valve stem, then the bored sealing part, and then press the washer 18 tightly against the end of the nipple, to prevent leakage of 40 lubricant between the nipple and nozzle, while lubricant is being forced through the nipple.

45 The gun may be disconnected from the nipple by turning the barrel 1 in a contra-clockwise direction. The pins 20, 20 ride up the inclined surfaces of the slots 21, 21 to press the valve 23 against the valve seat on the washer 31 and then continue in the straight 50 portions of the slots to uncouple the nozzle from the nipple. The lubricant under pressure in the barrel 1 presses the valve seat part 26 toward the valve 18 to make a lubricant-tight joint between the seat and valve so that 55 no lubricant can escape from the gun when not coupled with a nipple.

60 By permitting reciprocatory movement of the valve seat part 26, greater manufacturing tolerances may be allowed, because in closing 65 the valve the seat part may move whatever

70 slight variation there may be to permit the pins to enter the straight portions of the slots. Furthermore, the seat may be pressed by lubricant against the seat, whereas, if the seat were fixed, the exact movement of the valve toward its seat would require very accurate cutting of the slots and locating of the parts.

75 The gun is simple in construction (having very few and simple parts) and is easy to engage with and operate when engaged with a nipple. Similarly, it is a simple matter to disconnect the gun from a nipple while leaving pressure on the lubricant in the barrel 1. The coordinated pins and slots provide very 80 simple means for controlling the operations of coupling, valve opening, valve closing and uncoupling in their proper order.

85 While I have shown and described a preferred embodiment of my invention, it should be understood that I do not wish to be limited thereto, my invention being best defined in the following claims.

Claims:

1. Lubricating apparatus comprising, in 90 combination, a supply barrel, means for applying pressure to the lubricant in said barrel, a discharge nozzle for making a lubricant-tight joint with a lubricant-receiving nipple, a valve located between said barrel 95 and said nozzle and valve locking and releasing means rotatably mounted in said discharge nozzle and normally holding said valve in positive engagement with its seat when the lubricant in said barrel is under 100 pressure while being operable to permit opening of said valve by lubricant pressure so that lubricant may flow through said nozzle to the lubricant-receiving nipple.

2. Lubricating apparatus comprising, in 105 combination, a supply barrel, means for applying pressure to the lubricant in said barrel, a discharge nozzle having means for making a positive coupling lubricant-tight engagement with a lubricant-receiving nipple, a reciprocable valve located between said barrel and said nozzle, valve control means for holding said valve against its seat when said nozzle is not fully connected with the nipple, said valve control means being operable to permit the lubricant under pressure in said barrel to open said valve and flow through said nozzle to the nipple when said nozzle and nipple are completely coupled.

3. Lubricating apparatus comprising, in 120 combination, a supply barrel, means for applying pressure to the lubricant in said barrel, a discharge nozzle for making a lubricant-tight joint with a lubricant-receiving nipple, a valve normally preventing flow of lubricant 125 from said barrel to said nozzle, a reciprocable valve seat part, and valve control means rotatably mounted in said discharge nozzle and for preventing unseating of said valve when said nozzle is disengaged from the lubricant- 130

receiving nipple while being operable to release the valve and permit flow of lubricant from said barrel through said nozzle when engaged with the nipple.

- 5 4. Lubricating apparatus comprising, in combination, a supply barrel, means for applying pressure to the lubricant in said barrel, a discharge nozzle for making a lubricant-tight joint with a lubricant-receiving 70
10 nipple, a reciprocable valve, a cooperating reciprocable valve seat and coordinated means rotatably mounted in said discharge nozzle and for holding the valve against reciprocation while said seat is pressed against the 75
15 valve and for releasing the valve to permit it to be moved away from the seat so that lubricant may pass from said barrel through said nozzle to the nipple.

- 5 20 Lubricating apparatus comprising, in combination, a supply barrel, means for applying pressure to the lubricant in said barrel, a discharge nozzle for making a lubricant-tight joint with a lubricant-receiving nipple, a reciprocable valve, coordinated means rotatably mounted in said discharge nozzle and for holding said valve against reciprocation and for releasing said valve to permit reciprocation thereof, and a lubricant-pressed valve seat part adapted to make a lubricant-tight 80
25 joint with said valve when said valve is held against reciprocation.

- 6 30 Lubricating apparatus comprising, in combination, a supply barrel, means for placing under pressure the lubricant in said barrel, a nozzle sleeve, means carried by said sleeve for making a lubricant-tight seal with a lubricant-receiving nipple, a reciprocable valve carrying part, pin and slot means between said valve carrying part and said sleeve 85
35 and a lubricant-pressed valve seat part for making a tight seal with the valve to prevent escape of lubricant from the apparatus when not connected with a nipple.

- 7 45 Lubricating apparatus comprising, in combination, a supply barrel, means for placing under pressure the lubricant in said barrel, a nozzle sleeve rigidly connected to said barrel, means carried by said sleeve for making a lubricant-tight seal with a lubricant- 90
50 receiving nipple, an outwardly opening valve, means operable to prevent opening of said valve when said nozzle is not in lubricant-tight engagement with the nipple, and said means being operable to permit opening of said valve when said nozzle is in lubricant-tight engagement with the nipple.

- 8 60 Lubricating apparatus comprising, in combination, a supply barrel, means for placing under pressure the lubricant in said barrel, a nozzle sleeve rigidly connected to said barrel, means carried by said sleeve for making a lubricant-tight seal with a lubricant- 95
65 receiving nipple, an outwardly opening valve, means operable to prevent opening of said valve when said nozzle is not in lubricant-

tight engagement with the nipple, said means being operable to permit opening of said valve when said nozzle is in lubricant-tight engagement with the nipple and a lubricant-pressed valve seat presenting part for making a lubricant-tight contact with said valve.

9 70 A lubricant compressor comprising, in combination, a supply barrel, means for compressing the lubricant in said barrel, a nozzle, coupling and sealing means carried by said nozzle for lubricant-tight coupling engagement with a lubricant-receiving nipple, an outwardly opening valve part cooperating with said coupling and sealing means, and pin and slot means between the valve part 80
75 and nozzle part for controlling coupling and valve opening and closing.

10 80 A lubricant compressor comprising, in combination, a supply barrel, means for compressing the lubricant in said barrel, a nozzle, coupling and sealing means carried by said nozzle for lubricant-tight coupling engagement with a lubricant-receiving nipple, an outwardly opening valve part cooperating 85
85 with said coupling and sealing means, pin and slot means between the valve part and nozzle part for controlling coupling and valve opening and closing and a lubricant-pressed seat part reciprocable to a slight extent relative 90
95 to said valve part.

11 90 Lubricating apparatus comprising, in combination, a supply barrel, means for applying pressure to the lubricant in said barrel, a discharge nozzle for making a lubricant-tight joint with a lubricant receiving nipple, an outwardly opening valve, a control means for said valve, said valve control means being operable to permit the lubricant under pressure in said barrel to open said valve and flow through said nozzle to the nipple when 100
95 said nozzle and nipple are completely coupled.

12 100 Lubricating apparatus comprising, in combination, a supply barrel, means for placing under pressure the lubricant in said barrel, a nozzle sleeve, means carried by said sleeve for making a lubricant-tight seal with a lubricant-receiving nipple, a reciprocable valve carrying part, pin and slot means between said valve carrying part and said sleeve 110
105 and a lubricant-pressed valve seat part for making a tight seal with the valve to prevent escape of lubricant from the apparatus when not connected with a nipple, said seat part being reciprocable to a slight extent relative to said valve carrying part.

13 115 A lubricant compressor comprising, in combination, a supply barrel, means for compressing the lubricant in said barrel, a nozzle sleeve carried by said barrel and provided with a slot, means carried by said nozzle sleeve 120
125 for making a lubricant-tight seal with a lubricant receiving nipple, a valve carried in said sleeve, a valve control part rotatably mounted in said sleeve, and a pin carried by said valve control part adapted to engage said 130

slot, said valve control part being operable to permit opening of said valve when said nozzle sleeve is in lubricant-tight engagement with the nipple.

- 5 14. A lubricant compressor comprising, in combination, a supply barrel, means for compressing the lubricant in said barrel, a nozzle sleeve carried by said barrel and provided with a slot, means carried by said nozzle sleeve
- 10 for making a lubricant-tight seal with a lubricant receiving nipple, a valve carried

in said sleeve, a valve control part rotatably mounted in said sleeve, and a pin carried by said valve control part adapted to engage said slot, said pin and slot being adapted to cause said valve to be reciprocated to open or closed position upon relative rotation between said valve part and said nozzle sleeve.

15 In testimony whereof, I have signed my name to this specification. 20

HOWARD J. MURPHY.
